UNITED STATES PATENT OFFICE.

EDWARD L. REYNOLDS, OF NEW YORK, N. Y.

FLOOR CLEANING AND POLISHING MACHINE.

1,263,112.

Specification of Letters Patent. Patented Apr. 16, 1918.

Application filed August 11, 1917. Serial No. 185,658.

To all whom it may concern:

Be it known that I, EDWARD L. REYNOLDS, a citizen of the United States, and a resident of the borough of Manhattan, city, county, and State of New York, have invented certain new and useful Improvements in Floor Cleaning and Polishing Machines, of which the following is a specification.

My improvements relate to machines for cleaning and polishing floors, especially those having waxed surfaces; and the invention consists in the specific combination and arrangement of parts described and claimed, distinctive features being the use of a counterpoise weight for regulating the peripheral pressure exerted by the cylindrical brush on the surface with which it contacts, and the collection and storage, by partial vacuum, of particles precipitated by the brush,—the latter and the suction means being driven by the same motor, all as herein-after more fully set forth.

In the accompanying drawings,

Figure 1, is a plan of apparatus embodying the essential features of my invention, the upper portion of the handle being broken away;

Fig. 2, is a front elevation of the parts shown in Fig. 1;

Fig. 3, is a side elevation of the parts shown in Fig. 1, projected directly therefrom, and showing the handle complete.

The truck frame A, is supported in front by the axle b, of the cylindrical brush B, the latter performing the double function of floor rest, as well as of a sweeping, polishing, or scrubbing brush. The rear of the truck frame A, is supported on rollers r, r, the journals of which rest in bearings formed for them in the housings a, a, positioned at the rear corners of said truck frame A. These rollers r, r, are in alinement and constitute virtually the fulcrum of the lever H, which in turn constitutes the handle by which the truck A, is manipulated. On this hand lever H, is adjustably secured a counterweight W, by which the peripheral pressure of contact of the brush with the floor may be regulated to suit various conditions and requirements of use. Thus by loosening the set screw w, the weight may be moved toward or from the axes of the rollers r, r, and secured in any desired or prescribed position on the hand lever H, between the curve h' and the switch box h², (Fig. 3). Obviously if the weight W, is positioned as shown

in solid lines in the drawings it will exert greater leverage to relieve the peripheral pressure of the brush B, on the floor than if said weight W, is positioned, say, as shown 60 in dotted lines in Fig. 3, in which the leverage will be decreased and the peripheral pressure exerted by the brush increased.

The brush B, is rotated clock-wise, or with the line of travel, that is, forwardly and upwardly, by a motor M, mounted on the truck frame A, and preferably of the electrical type, the wires thereto extending from the switch box h², through the hollow hand lever H, and from said switch box h², by suitable 65 cable to a source of electrical supply in a manner well known in the art. Thus in the drawings the armature shaft m, is provided with a sprocket wheel m', which actuates a sprocket chain n, engaging with a 70 sprocket wheel b', on the axle b, of the brush B, it being understood that the said brush is secured to rotate with said axle b.

As before intimated the brush is rotated forward and upward as indicated by the 80 arrows, and consequently dust is projected by the brush in the line of travel when the truck A, is pushed forward by means of the hand lever H. For this reason I position the nozzle e, of a suction tube e', across the 85 lower front of the brush B, adjacent to the line of contact of the brush with the floor, as shown more particularly in Fig. 3, so that such dust and extraneous matter is immediately collected and withdrawn from beneath 90 the brush instead of being precipitated into the space in front thereof to be dissipated through the atmosphere.

The suction tube e', extends over the brush B, to an exhaust fan or equivalent E, 95 by which the dust, etc., is delivered to a receptacle or container C, adapted to retain solid matter while allowing the escape of air. This container C, may be of any desired form and construction, and is herein represented only symbolically as a means of receiving the discharge from the suction device E.

The latter is driven directly by the motor M, by means of bevel gearing as shown in 105 Fig. 1, of the drawings, or by any other mechanical expedient adapted to transmit power from the motor M, to the exhaust device E.

What I claim as my invention and desire 110 to secure by Letters Patent is,

Floor cleaning and polishing apparatus of

the character designated, comprising a truck frame, a cylindrical brush mounted on the forward portion thereof and supporting said forward portion, a suction nozzle positioned 5 in front of and in close proximity to said brush and connected with an exhaust device, said exhaust device supported by said truck frame, a motor mounted on said truck frame, means for rotating said brush forwardly and 10 upwardly and driving said exhaust device simultaneously by power derived from said

motor, a fulcrum roller support for the rear portion of said truck frame, a hand lever attached to and extending rearward from said truck frame and beyond the said fulcrum roller support, and an adjustable counter-weight on said hand lever, for the purpose described.

EDWARD L. REYNOLDS.
